UNITED STATES PATENT OFFICE.

FREDERIC B. KOLLBERG, OF BISBEE, ARIZONA.

RIFFLE-TABLE FOR CONCENTRATING APPARATUS AND METHOD OF CONSTRUCTING THE SAME.

1,168,009.

Specification of Letters Patent.

Patented Jan. 11, 1916.

Application filed April 12, 1915. Serial No. 20,913.

To all whom it may concern:

Be it known that I, FREDERIC B. KOLLBERG, a citizen of the United States, and a resident of the town of Bisbee, county of Co-
5 chise, and State of Arizona, have invented certain new and useful Improvements in Riffle-Tables for Concentrating Apparatus and Methods of Constructing the Same, of which the following is a specification.

10 My invention relates to riffle tables for concentrating apparatus, and has for its object the production of a table cover which will be of improved construction, and efficient in operation.

15 A further object is the production of a table cover which will be of durable and economical construction, and one which will permit of a simple method of construction.

Other objects will appear hereinafter.

20 With these objects in view, the invention consists in the combinations and arrangements of parts hereinafter described and claimed.

25 The invention will be best understood by reference to the accompanying drawing forming a part of this specification, and in which,

30 Figure 1 is a top plan view of a fragment of a riffle table embodying the invention, and Fig. 2 is a section taken on line $x-x$ of Fig. 1.

35 The construction illustrated in the drawing comprises a table 1 which is of the usual construction. Said table is shown as being provided with side boards or flanges 2 at its longitudinal edges, but these side boards form no part of the invention, and may or may not be used in conjunction with the table.

40 Provided upon the upper side of the table 1 are spaced riffles which are arranged according to any standard method desired, each of said riffles comprising a base section 3 secured to the table by nails 4, and

45 an upper section 5 secured to the section 3 by nails 6. Arranged upon the table 1, in the spaces between the riffles, is a layer 7 of cement the upper surface of which is flush with the upper edges of riffle sections

50 3, as clearly shown in Fig. 2. In the construction of the table cover, the base sections 3 of the riffles are first secured in position. The cement is then introduced into the spaces between the sections 3 and leveled off so as to be flush with the upper edges

of said sections, a suitable straight edge being used in the leveling-off process, as will be understood by those skilled in the art. After the cement has set, the riffle sections 5 are secured to the exposed upper edges of 60 the sections 3.

Through the alternating arrangement of the cement and riffles, a construction is provided in which a thin sheet or layer of cement may be placed upon the upper surface of the table without fear of the cement cracking or buckling. Also, with this arrangement the wooden riffles in addition to serving as a means of anchoring the cement in position, permit also of contraction and 65 expansion of the same under different temperatures. The cement forms an ideal wearing surface and will be perfectly smooth and flat. Through the sectional construction of the riffles, it will be seen that, the 70

application of the layer of cement to the upper side of the table between the riffles may be effected with ease and expedition, it being clear that without the sectional construction of the riffles, the leveling-off of 75

the layer of cement between adjacent riffles would be a tedious and laborious undertaking. The cement also serves to securely 80 anchor the base sections of the riffles in place affording a secure and rigid base on which to secure the upper riffle sections. Also, the 85

sectional construction of the riffles permits of easy and ready removal of the upper sections for renewing the same when worn.

While I have illustrated and described 90 the preferred form of construction for carrying my invention into effect, this is capable of variation and modification without departing from the spirit of the invention. For instance, it is understood that the riffle 95 table cover is not limited to its use in connection with the specific form of table shown, nor the specific arrangement or disposition of the riffles upon the table, but I desire to avail myself of such variations 100 and modifications as come within the scope of the appended claims.

Having described my invention what I claim as new and desire to secure by Letters Patent is:

1. In concentrating apparatus, the combination of a table; riffles spaced on said table, each of said riffles being formed of two superimposed sections; and a layer of plastic material on said table arranged between 110

said riffles, said layer being of a thickness substantially the same as the height of the lower sections of said riffles, substantially as described.

- 5 2. In concentrating apparatus, the combination of a table; riffles spaced on said table, said riffles being formed of base sections and sections fastened to the upper sides of said base sections; and a layer of plastic material 10 arranged on said table between said riffles, said layer being of a thickness substantially the same as the height of the base sections of said riffles, substantially as described.

- 15 3. In concentrating apparatus, the combination of a table; transversely extending riffles spaced on said table, each of said riffles being formed of two superimposed sections; and a layer of plastic material on said table positioned between said riffles, said layer being of a thickness substantially the same as the height of the lower sections of said riffles, substantially as described.

- 20 4. In concentrating apparatus, the combination of a table; riffles spaced on said table, each of said riffles being formed of two superimposed sections; and a layer of cement 25 on said table arranged between said riffles, said layer being of a thickness substantially the same as the height of the lower sections 30 of said riffles, substantially as described.

5. In concentrating apparatus, the combination of a table; riffles spaced on said table, said riffles being formed of base sections of uniform height and sections fas-

tened to the upper sides of said base sections; and a layer of plastic material on said table between said riffles having its upper surface flush with the upper sides of said base sections, substantially as described.

6. The method of constructing a concentrating apparatus comprising a table having spaced riffles thereon each of which consists of two superimposed sections, and a layer of plastic material on the table arranged between said riffles, which consists in first applying the lower sections of said riffles to the table; then filling in the spaces between the lower riffle sections with the plastic material; then leveling said plastic material off flush with the upper edges of said lower riffle sections; and in subsequently applying the upper riffle sections to the upper edges of said lower riffle sections, substantially as described.

7. In concentrating apparatus, the combination of a table; riffles spaced on said table; and a layer of plastic material on said table arranged between said riffles, said riffles protruding from said layer of plastic material, substantially as described.

In testimony whereof I have signed my name to this specification in the presence of two subscribing witnesses.

FREDERIC B. KOLBERG.
